(57) **CLAIM**

The ornamental design for a home plate, as shown and described.

DESCRIPTION

The present application is also related to U.S. Patent Application Ser. No. 11/129,826, filed May 16, 2005, entitled Method for Using a Home Plate Tape Measure, now abandoned.

FIG. 1 is a back top perspective view of a third embodiment of the home plate showing my new design.

FIG. 2 is a front bottom perspective view of the home plate of FIG. 1.

FIG. 3 is a top plan view of the home plate of FIG. 1; and, FIG. 4 is a bottom plan view of the home plate of FIG. 1. The broken lines in the drawings are for illustrative purposes only, and do not form part of the claimed design.
